US0D1032646S

(12) **United States Design Patent** (10) Patent No.: US D1,032,646 S
Mead et al. (45) Date of Patent: ** Jun. 25, 2024

- (54) **DISPLAY SCREEN WITH GRAPHICAL USER INTERFACE FOR FLUID MIXING APPARATUS** G06F 3/0486; G06F 3/0488; G06F 3/04886; G06F 9/4443; G06F 17/211; G06F 17/212; G06F 9/451; G06Q 10/10; G06Q 50/01; H04N 21/4312; H04N 21/4438; H04N

(71) Applicants: **Life Technologies Corporation**, Carlsbad, CA (US); **Life Technologies Holdings PTE Limited**, Singapore (SG) (Continued)

(72) Inventors: **Joshua Mead**, San Diego, CA (US); **Scott Rickes**, San Diego, CA (US); **Sean Zimmerman**, Encinitas, CA (US); **Alessandra Barbosa**, San Diego, CA (US); **Mio Ling**, Singapore (SG); **Woon Liang Soh**, Singapore (SG); **Kevin Mullen**, Smithfield, UT (US); **Christopher Brau**, Grand Island, NY (US); **Jordan Cobia**, Wellsville, UT (US); **Harmon Cosme Sicut, Jr.**, Singapore (SG) (56) **References Cited**
